MINER'S TOOL

Filed Feb. 25, 1929

Inventor

Joseph Kaiser

By Clarence A. O'Brien
Attorney

UNITED STATES PATENT OFFICE

JOSEPH KAISER, OF AUGUSTA, WISCONSIN

MINER'S TOOL

Application filed February 25, 1929. Serial No. 342,501.

This invention relates to a combination tool designed more especially for use by miners or blasters, for cutting and splitting fuses and the like, for crimping the caps upon the fuses and forming the holes in the explosive cartridge for the reception of the cap fuse, the primary object of the invention being to provide a tool of this character, provided with an improved cutting means capable of either cutting the fuses into the desired length or splitting their ends as may be desired.

A further object of the invention is to provide a miner's and blaster's tool of the class described capable of many uses from the fewest possible number of parts, durable, and one well adapted for the purpose to which it is designed.

The above and numerous other objects and advantages will present themselves from a study of the following description taken in connection with the accompanying drawings, wherein:

Figure 1 is a side elevation of the tool.

Figure 2 is an edge elevation thereof.

Figure 3 is a sectional view taken on lines 3—3 of Figure 1, and

Figure 4 is a sectional view taken on line 4—4 of Figure 1.

When reference is had to the drawing it will be seen that my improved tool consists of two members, A and B, pivoted together as at C and in its general appearance to resemble a pair of pliers. Each of the members A and B are provided with a jaw portion 2 and a handle portion 1 respectively, and it will be seen that one of the jaw portions 2 may be beveled at its inner end as at 3 to form a cutting edge. The inner edge of the cooperating jaw is of substantially the same thickness as the entire jaw. This construction of the jaw is best shown in Figure 3 of the drawing. The purpose of providing one of the jaws with a flat marginal edge such as at 4 is to provide a substantially flat support for the fuse when the fuse is inserted between the jaws either to be cut in length or to split the ends of the fuse to facilitate the ignition of the outer end of the fuse.

Oppositely disposed notches 6 are formed in the handle portions 1 of the members A

and B and disposed in cooperating, opposing relation on the inner edges of both these members adjacent their pivotal connection. These notches 6 constitute means for crimping the cap upon the fuse end. The handle portion 1 of the member A tapers at its outer end to terminate in a point 7, which point may be used for punching a hole in the cartridge or for other work common to securing the fuse in place in blasting work. Formed, preferably on the handle portion B is an elongated groove 8 which groove extends longitudinally of the handle and is provided with an inclined roughened surface 9. This slot and its roughened surface provides means for igniting a match and is capable of use in rainy or windy weather.

Further attention is called to the handle portion 1 of the member B wherein it will be seen that the handle is formed at its outer end with an inwardly extending projection 10, said projection extending at right angles to the handle proper. Formed within this handle intermediate the projection 10 and 75 the elongated recess 8 is formed a bore 11 extending transversely of the handle and provided with openings on the opposite edges of the handle. The purpose of this bore is to form a seat for the reception of a fuse shown in dotted lines in Figure 1 of the drawing, while the projection 10 forms a rest or support against which the fuse may be urged by one finger of the operator, for maintaining the end of the fuse to be ignited in the bore.

As shown to advantage in Figure 1, when the fuse is inserted in the bore 11, the taper or winch of the fuse terminates within the bore at the end of the groove 9, so that when lighting the fuse, the flame will be shielded somewhat from the wind, thus facilitating the lighting of the fuse during windy or rainy weather.

From the above description it will be seen that I have provided a tool suitable for use by miners and blasters, which is of simple construction, durable, and well adapted for the purpose intended.

Having thus described the invention, what

I claim as new and desire to secure by Letters Patent is:—

- 5 1. In a tool of the class described, a handle member, said handle provided with a longitudinally extending recess, said recess having a bottom wall extending obliquely with respect to the longitudinal axis of said handle, said bottom wall being adapted to provide a match igniting surface, said handle at the lowermost end of the bottom wall of said recess being provided with a transverse bore communicating with said recess, said bore adapted to receive therein a fuse to be ignited with the wick of the fuse terminating within the bore.
- 10 15 2. In a tool of the class described, a handle member, said handle provided with a longitudinally extending recess, said recess having a bottom wall extending obliquely with respect to the longitudinal axis of said handle, said bottom wall being adapted to provide a match igniting surface, said handle at the lowermost end of the bottom wall of said recess being provided with a transverse bore communicating with said recess, said bore adapted to receive therein a fuse to be ignited with the wick of the fuse terminating within the bore, said handle being further provided with a lateral projection adjacent
- 20 25 30 35 40 45 50 55 60 65

In testimony whereof I affix my signature.

JOSEPH KAISER.
